UNITED STATES PATENT OFFICE.

GEORGE HOLT FRASER, OF BROOKLYN, NEW YORK.

SEPARATOR.

1,317,014.

Specification of Letters Patent. Patented Sept. 23, 1919.

Application filed August 27, 1914, Serial No. 858,797. Renewed December 18, 1918. Serial No. 267,401.

To all whom it may concern:

Be it known that I, GEORGE HOLT FRASER, a citizen of the United States, residing at No. 226 Quincy street, in the borough of

5 Brooklyn, county of Kings, city and State of New York, United States of America, manufacturer, have invented certain new and useful Improvements in Separators, of which the following is a specification.

10 This invention relates to apparatus for separating, sizing, or classifying materials by means of a fluid current, and aims to provide certain improvements therein, and in processes therefor.

15 Heretofore it has been common to separate fine from coarse material by an air current, by passing the material through a casing in which the current was drawn through the material to float out the fine particles and 20 deposit these in a dust chamber, after which the current was returned and continuously re-used.

25 With apparatus of this character it has been difficult to prevent coarse particles from being carried out with the fine, and to prevent variations in product due to changing conditions.

30 This invention relates to apparatus in which a fluid current is utilized to effect separation, and aims to provide improvements whereby one or more products may be separated with greater convenience and certainty than heretofore.

35 To this end in carrying out the preferred form of the present improvements the material to be treated is formed into a descending blanket, alternately concentrated and expanded as it descends by gravity, intermittently retarded and re-distributed to avoid 40 any undue acceleration, and sufficiently agitated to expose all portions to current action, and while subject to these conditions a fluid current is passed through it to float outwardly from the descending blanket all 45 material capable of floating in the prevailing current. The remaining material descending through the current is withdrawn as tailings.

50 The extracting process to insure removal of all fine material involves the risk of carrying out some oversize, and this invention preferably provides for selecting from the extracting current such grade or grades of material as desired and insuring that the 55 final product shall be free from objectionable sizes.

The invention further provides for more

completely utilizing the space necessarily occupied by the apparatus, for outside current producing provision, for greater accessibility, and for convenience of cleaning, agitation and removal of parts, and it provides various features of improvement, all of which will be hereinafter more fully set forth, and described in detail in their preferred form, with reference to the accompanying drawings, which illustrate the preferred adaptation of my present invention, and in which—

55 Figure 1 is a vertical axial section, cut approximately on the line 1—1 of Figs. 2 and 3 of an air separator constructed according to the preferred form of my invention, and

60 Fig. 2 is a horizontal section thereof cut approximately on the planes of the lines 2—2 of Fig. 1, and

65 Fig. 3 is a horizontal section thereof cut approximately on the planes of the lines 3—3 of Fig. 1.

70 Referring to the drawings:

Let A indicate the casing, B the driving mechanism, C the feed hopper, D the distributor, E the feed chamber, F the blower, G the dust chamber, H the return passage, I the coarse outlet, and J the fine outlet, of an air separator. All of these parts may be of any usual or suitable construction adapted to distribute the material in a descending blanket, cause a fluid current to traverse 80 it, precipitate the fine material floated out by the current, continuously re-use the fluid medium, and separately deliver the coarse and fine products.

85 The casing A shown consists of a cylindrical body a, a flat top b, a conical bottom c, and a separable conical end d in which are formed the coarse and fine outlets, and all forming an inclosed chamber in which the fluid is confined.

90 According to one feature of my invention the driving mechanism comprises a tubular shaft K mounted in upper and lower bearings e in a bracket f mounted on cross-beams g which support the separator. Slidingly or removably keyed or carried on the shaft K is a cone or step wheel h driven from a similar wheel i by a belt j, or other suitable variable speed driving provisions.

95 The shaft K has a shoulder k seating on a split collar l which supports it vertically on a ring, ball or other non-friction annular thrust bearing m, which is centered upon and supported by lower bearing e. The

lower end of the shaft K is reduced so that it can be passed through the vertical bearing and extends into the casing, and has screwed or otherwise separably connected to it a flange o to which the spider p is bolted or otherwise separably connected so as to revolve with the shaft.

The frame f is shown in Fig. 1 as open at its front side so that the shaft may be removed horizontally and then raised vertically, it and the hopper above sliding horizontally into the open side of the frame.

The hopper C is movable rotatively and adjustably mounted on the frame f and has a tubular extension q telescopically and adjustably entering the feed pipe L, which latter is adjusted vertically by screws r and passes freely through the tubular shaft K opening at its lower end opposite the feed disk s of the distributer from which it can be adjusted to regulate or control the speed of feed. This disk is adjustably and separably connected to the spider p by screws n, and revolves with the shaft K so that material falling on it is thrown out centrifugally and horizontally into the feed chamber.

The distributer D may be any suitable device for feeding the material in a thin blanket or wide thin stream, according to whether the blanket of material to be treated is to descend in a rectilinear or tubular path. It is preferably a driven member, and when the material is to descend by gravity in the form of a tubular blanket the distributer is preferably revolved to throw it outwardly to its path of descent.

I prefer to form the feed chamber E as a circular or annular chamber surrounding the distributer and bordered by a baffle plate shown as a cylindrical ring t against which the material strikes and which is removable for renewal.

Below the baffle ring my invention preferably provides a contracting or feeding ring or plate u, upon which the material falls from the baffle ring and by which it is directed inwardly and delivered onto the first of a series of retarding or distributing rings or members v which check the speed of flow and deflect the material outwardly allowing it to fall onto a second converging or deflecting ring or plate u down which the material flows and from which it falls onto the next plate v, the contracting and discharging plates or rings being arranged in succession so that the material will flow down one and fall onto the other, be retarded thereby and again fall onto the next, and so on throughout the series of feeding plates whereby the material descending by gravity between them traverses a sinuous path and is alternately retarded and re-started so that undue acceleration of speed of flow is prevented and sufficient agitation is ob-

tained, as the material descends between the plates. When these are arranged in ring form as shown the material descending between them constitutes an endless blanket or tubular envelop between the distributer 70 and the tailings cone M below them, and the space between the rings or plates constitutes an annular sinuous separating passage N.

The rings v are relatively short and the rings u are preferably long or upwardly extended to bring their upper edges above the lower edges of the next upper ring v, and preferably to or above the lower edge of the next upper ring u, so that the current in passing between two rings u must rise as it 80 traverses the passage O and any heavy particles carried out horizontally by it may be dropped onto the upper part of the ring u as the current rises to pass over the top thereof.

For some work where further selection is unnecessary the series of rings u and v only may be used in connection with the current producing and dust collecting provisions, but I prefer to provide for further 90 selecting the material thus separated, and preferably for separately classifying or grading these selections according to their number. My invention provides for this one or more successive selectors, preferably 95 annular and parallel with the primary feeding and retarding members and concentric with and surrounding these intermediate of the pressure and exhaust chambers. Preferably this is accomplished in the manner 100 shown by interposing a reversely inclined plate or ring w opposite each passage O, which intercepts the outflowing current and deflects it downwardly at an acute angle, and by interposing the succeeding plate or ring x outwardly of and spaced apart from the adjacent ring w which again intercepts the current and deflects it upwardly, so that the current travels approximately horizontally and preferably slightly upwardly in a 105 sinuous path as it expands outwardly, and large pieces carried by it will be intercepted and fall or be thrown out of it as the current turns around the edges of the rings w and x in passing these. These rings are slightly 110 spaced apart above and below each passage to permit particles thus precipitated or selected to descend between them and are sufficiently spaced apart to give the desired width of passage for the current. Particles extracted between these rings will descend 115 crossing the current for each succeeding passage so that should any fines escape with them the current of a succeeding passage may extract these.

These rings or plates constitute a selector R, and their product may be separately received and withdrawn by a selector cone S through a passage T and outlet U.

Ordinarily one selector succeeding the 130

initial separating device will suffice, but for some purposes a plurality of successive selectors, or differential classifiers or graders, may be desirable, and my invention preferably comprises two or more of these between the final and initial extracting, which is preferably accomplished by providing another plate or ring y in the passage O beyond the selector R , which again deflects the outflowing current downwardly against a cone or wall z . The current from the several passages O discharges within this wall and flows upwardly over the top of the wall and down into the chamber Q . This wall z constitutes a second selector V , the tailings of which may be separately collected as shown by a cone W and passage X and outlet Y when this grade is desired.

Proportioning, inclination, relative elevation, and intermediate spacing, of these several parts will be suited to circumstances or requirements, but are preferably such as to effect varying current speeds as well as considerable changes of direction in the current as it progresses outwardly, and in the final selection chamber the area is sufficient to give such volume as will insure a current speed suited to float only particles of the fineness desired in the finest product to be produced so that only this will be carried into the chamber Q and can reach the dust chamber G .

In the chamber Q the current descends with comparative slowness, its floating dust being precipitated by gravity into the settling chamber for removal through the fine outlet.

The air is withdrawn from the chamber Q or returned to the chamber P through the return passage H , which communicates between these and preferably exhausts by suction from the inner side of the chamber Q . I preferably for better disclosing their utilization, illustrate my present improvements as used in connection with my improved means for mechanical extraction or filtration of floating particles from the fluid intermediate of the chamber Q , and the return H in which I prefer to provide a foraminous or interstitial wall between these through which the current must pass, and this is preferably a double wall or series of hollow troughs or plates disposed with their concave sides facing the chamber Q and their convex sides facing the inlet H and extending downwardly and outwardly from the cone W constituting the top wall of the return, the cone a' constituting its bottom wall. These plates b' are staggered in relation and spaced apart so that circuitous passages c' exist between them through which the current may flow while their hollow faces will provide a space in which particles may settle and descend without danger of being floated by eddies into the

return. The open lower ends of the troughs b' discharge into the dust chamber where there is practically no current sufficient to lift their dust. Thus the returning current is sufficiently freed from floating back fines to 70 avoid any loss of efficiency on this score, so that the current may be strong enough to extract all the fines without danger of material loss of efficiency, and the selectors may be used to extract large pieces in such a 75 strong current before they reach the dust chamber.

Any suitable current producing means and connection may be utilized with those features of my improvements already described, 80 but I prefer to employ an outside blower or one separate from and independent of the feeder, and to drive this and the latter from the same source of power, preferably a motor Z , coupled to the shaft a' of the blower F , 85 which shaft is shown as extended to the pulley i for driving the feeder.

The suction and discharge connections between the outside blower and the chambers Q and P may be made in any suitable way, 90 but according to the preferred form of my invention I provide for utilizing centrifugal action to equalize the outflow and inflow of current and avoid undue variations or inequalities thereof, and to preserve a uniform 95 suction throughout the exhaust chamber Q . This is preferably accomplished by connecting the suction pipe e' of the fan tangentially with an annular exhaust passage f' outwardly of and surrounding the distributing and contracting inlet g' of the return and communicating with the latter by a reverse passage h' over an intermediate annular dam i' , so that the suction current from the trough f' will cause a rapid whirling 100 action in the latter which will prevent excessive withdrawal of air at any one point around the sinuous annular passages communicating between this and the inlet passage H .

My invention provides a similar means for utilizing centrifugal force to equalize the blast as the current comes from the blower to the chamber P which is preferably accomplished by connecting the blast pipe j' of the blower tangentially to an annular blast chamber k' in which the blast will whirl and uniformly discharge over the inner wall or cone l' and down through the passage m' to the open end n' of the main 110 tailings cone M , through which as it rises it will still be subjected to some whirling action which will aid in avoiding excess of current at any one point.

In this way an outside blower as distinguished from one inclosed within the casing and revolving with the distributor may be utilized at a great saving of power and much simplification of construction, and the desired blower and distributor feeds and 120 125 130

- adjustments may be had independently, and the blower need not be subjected to great wear from direct contact with the material, as it can operate only on the cleanest air.
- 5 My invention provides for utilizing much of the space within the bottom cone which is not all needed for precipitation of dust, and preferably accomplishes this by locating both the annular suction chamber and 10 its communicating passages, and the annular blast chamber, and its communicating passages as well as the intermediate selector passages, all within the dust chamber, and the blast chamber within the suction chamber, so that these all are concentrically superposed and compactly nested around the tailings and selector passages, and the blower may be placed where desired and suitably connected with them.
- 15 20 When used as separate passages the selector passages are preferably disposed between the suction and blast equalizers by a series of cones spaced apart to give the necessary intermediate passage and suitably connected and separated for convenience and manipulation. As shown the cone o' held on the cone d serves as the inner wall of the dust chamber G and connects with the outlet Y and with the secondary selector passage X .
- 25 30 Loosely setting on it is a reverse cone p' serving as the top of the latter passage and the inner wall of the suction chamber f' and loosely setting on this is a cone q' constituting one outer wall of the latter, the top wall 35 of which is the cone r' , all of these cones being suitably supported and mounted so that each can be vibrated or lifted and are movable for cleaning.
- When my present improvements are used 40 45 with my improved filter as shown, the inner troughs b' are preferably rigidly connected to the cone W and supported at their lower ends against the cone a' , but the outer row of troughs are movably or elastically connected at their upper ends to the cone W as by springs c^2 , which poised them resiliently so that they may quiver in use to clean themselves, and their lower ends bear against the cone c . The cone c is preferably 50 55 sectionalized by a section f^2 separably connected so that it can be removed to permit the removal of the interior cones.
- Where advisable the edges of the cones are slightly spaced to permit settling to 60 65 drift through and where necessary their edges are valved with a flap d^2 or flexible strip to avoid current leakage while permitting gravity flow of precipitated material.
- The outer wall of the blast chamber bears 70 75 a cone s' carrying the outlet I and serving as the inner wall of the passage T , and on this cone is mounted the cone t' which serves as the top wall of the blast chamber and isolates it from the passage. The cone 80 85 M serves as one inner wall of the blast chamber and the reverse cone u' as its bottom wall. Between the cones s' and o' is a cone v' used when the tailings from each selector are to be separated and which constitutes the intervening wall between their outlets, 90 95 on which cone is a cone w' partitioning the passages T and X between the cone v' and the cone S . While these cones may be fixed together I prefer to loosely separably and suitably connect and support them so that they may be readily vibrated, adjusted or removed. The spacers between them constitute impact or jarring posts or members, by hammering on which percussively they may be vibrated to loosen adhering material. 100 Adjustable separable screws e^2 under the cones o', v' and s' support these.
- My invention provides for accessibility to the several parts of the device by the operator without substantial manipulation, 105 and for this purpose I preferably construct the tailings outlet I with a large tubular passage x' closed by a cover v' by opening which a man can crawl in and pass through the interior of the separator to adjust, repair or clean it. Similarly the suction and blast passages e' and j' are made respectively with a door z' in direct line with them and of sufficient size to permit entrance of the body so that the operator can crawl in either 110 the suction or exhaust equalizer.
- Several cones are preferably suspended by rods A' from the top b and positioned centrally by divergent bars a^2 and b^2 from the side. 115
- In operation the speed of feed entering from the hopper C will be controlled by adjusting the feed pipe L toward the feed disk s or by regulating the speed of the latter by its driving mechanism. The current will be controlled by the speed of the fan or by a butterfly valve B' or otherwise. The removable cones t' and w' will be used if the selector tailings or either of them are 120 125 to be separately withdrawn.
- Current rising into the chamber P will flow out between the rings v , traverse the blanket of descending material, extract the fines and float them out through the passage O . The selectors R and V when and if used will make their proper selections and classifications, and the floating fines passing these will descend through the chamber Q and fall into the dust chamber G , the air carrying these being drawn through the filter 130 (when my present improvements are used in connection with this) and clarified on its way to the return passage H . The exhaust through the latter will be uniform. Any sediment settling within the exhaust chamber will leak through the cracks thereof and fall into the dust chamber. The blast by reason of its centrifugal action will exert a uniform pressure as it flows over and under the walls and rises within the cone M and 135

into the chamber P. Any dust settling in the blast passage will leak through into the main tailings outlet. The feed and withdrawal will be constant, and once adjusted 5 to the work operation may continue without change regardless of variations in quantity or quality. A sufficient current to insure complete extraction can be used without danger since the selectors will eliminate 10 any large particles blown out at the first extraction. Efficiency will be increased when my present improvements are used in connection with my improvements in internal filtration.

15 It will be seen that my invention provides improvements which can be readily and advantageously availed of and it will be understood that the invention is not limited to the particular details of construction, arrangement or combination of parts, set forth as constituting its preferred embodiment since it can be utilized in whole or in part according to such modifications as circumstances or the judgment of those skilled 20 in the art may dictate without departing 25 from the spirit of the invention.

When feed to the hopper C includes material too coarse for passing through the separator a scalper C' is used, which may be any 30 suitable scalper, but, for better disclosing my present improvements I have illustrated them as used in connection with my improvements in scalping means which comprise a slotted foraminous plate or screen 35 bent into steps intermediate of the longitudinal extent of its elongated slots, so that the lower bent portion constitutes an outlet for each slot to permit escape of nails or hanging pieces, which is disposed with its 40 long faces or steps at approximately 45 degrees inclination and its intermediate portions at approximately right angles thereto, and mounted in a trough or chute B' of greater inclination than the scalper, and 45 which is preferably combined with a dam or retarder D' opposite each step to prevent too rapid flow. The large pieces scalped out of the feed descend past the separator to a spout E'.

50 The suction and blast pipes are separably connected to the blower, and the corresponding passages of the blower are provided with separable walls or hinged manhole doors z¹, see Fig. 3, so that either can be opened or 55 removed for access.

The scalper, having slots narrower than the selector outlets, guards these against possible oversizes.

60 For the purpose of more completely disclosing the scope and applicability of the features incident to this invention which I prefer to claim in this application many features of improvement in separating, sizing and collecting machinery are herein 65 shown and set forth but not specifically

claimed in this application, being the subjects matter of claims in my applications Serial Numbers:

What I claim is:

1. In combination, a casing, means outside of said casing for causing a fluid current to flow therein, means for causing material to descend therein in a downward path across the direction of flow of such current, extracting means in said casing comprising upwardly and downwardly extending members at one side of said path having a lower outlet for coarse particles and affording between them an outwardly extending sinuous current passage successive to said downward path of such descending material for receiving said current beyond said path for extracting coarse particles carried by said current, a settling chamber succeeding said extending means and in communication with said passage, and means communicating between said settling chamber and the other side of said path. 90

95 2. In combination, a casing, means outside of said casing for causing a fluid current to flow therein, means for causing material to descend therein in a downward path across the direction of flow of said current, extracting means comprising upwardly and downwardly extending members affording a lower outlet for coarse particles and affording a plurality of horizontally extending sinuous current passages for receiving said current successive to the downward path of such descending material for extracting coarse particles carried by said current, and a settling chamber succeeding said extracting means and in free communication 100 with two of said passages.

110 3. In combination, a casing, means outside of said casing for causing a fluid current to flow therein, means for causing material to descend therein in a downward path across the direction of flow of said current, selecting means within said casing at one side of said path comprising upwardly and downwardly extending members providing a lower outlet for coarse particles 115

120

125

130

and a horizontally extending sinuous current passage for receiving said current successive to the downward path of such descending material for extracting coarse particles carried by said current, a settling chamber succeeding said selecting means and in communication with said passage, and means affording an adjustable return passage communicating between said settling chamber and the interior of said casing at the other side of said path.

4. In combination, a casing, means outside of said casing for causing a fluid current to flow therein, means for causing material to descend therein in a downward path across the direction of flow of said current, means within said casing and at one side of said path providing a lower outlet for precipitated material and affording a sinuous passage for receiving said current successive to the downward path of such descending material for extracting particles carried by said current, and means affording a closed return passage receiving current leaving said sinuous passage and returning it to the interior of said casing at the other side of said path.

5. In combination, a casing, means outside of said casing for causing a fluid current to flow therein, means for causing material to descend therein in a downward path across the direction of flow of said current, selecting means within said casing providing a lower outlet for coarse particles and affording a sinuous current passage for receiving said current successive to the downward path of such descending material for extracting coarse particles carried by said current, a settling chamber succeeding said selecting means and in communication with said passage, a return passage, means affording a downward conduit for coarse material descending through said path, and means affording a separate downward conduit for particles extracted by said selecting means.

6. In combination, a casing, means outside of said casing for causing a fluid current to flow therein, means for causing material to descend therein in a downward path across the direction of flow of said current, selecting means at one side of said path providing a lower outlet for precipitated particles and affording a sinuous current passage for receiving said current successive to the downward path of such descending material for extracting coarse particles carried by said current, means affording a downward passage, communicating with said passage, succeeding said selecting means, means affording a settling chamber below and communicating with said downward passage, and means affording a current outlet from said downward passage intermediate of its extremities.

7. In combination, a casing, means outside of said casing for causing a fluid current to flow therein, means for causing material to descend therein in a downward path across the direction of flow of said current, selecting means providing a lower outlet for precipitated particles and affording a sinuous current passage for receiving said current successive to said path for extracting coarse particles carried by said current, supplementary selecting means providing a lower outlet for precipitated material and affording a sinuous current passage for receiving said current from and successive to said first mentioned sinuous passage for extracting particles carried by said current, a settling chamber succeeding said supplementary selecting means and in free communication with said sinuous passage thereof, and a return conduit for said current.

8. In combination, a casing, means outside of said casing for causing a fluid current to flow therein, means for causing material to descend therein in a downward path across the direction of flow of said current, selecting means at one side of said path comprising a plurality of upwardly and downwardly extending superposed members providing lower outlets for precipitated particles and affording superposed sinuous current passages for receiving said current successive to said downward path for extracting particles carried by said current, and means affording a current passage successive to and communicating with a plurality of said sinuous passages receiving current therefrom for delivering it to the other side of said path.

9. In combination, a casing, means outside of said casing for causing a fluid current to flow therein, means for causing material to descend in a downward path in said casing across the direction of flow of said current, selecting means within said casing at one side of said path providing a lower outlet for particles and affording a horizontally extending sinuous current passage for receiving said current successive to the downward path of such descending material for extracting particles carried by said current, and means affording a communicating passage receiving current from said sinuous passage and delivering it to the other side of said path.

10. In combination, a casing, means outside of said casing for causing a fluid current to flow therein, means for causing material to descend therein in a downward path across the direction of flow of said current, selecting means in said casing at one side of said path affording a sinuous current passage successive to said downward path for receiving said current beyond said path for extracting particles carried by said current and affording an out-

let for such particles below an intermediate portion of said passage, a settling chamber underneath said selecting means and in communication with said passage, and means below said selecting means affording a partition between the latter and said settling chamber.

11. In combination, a casing, means outside of said casing for causing a fluid current 10 to flow therein, means for causing material to descend therein in a downward path across the direction of said flow, selecting means at one side of said path affording a sinuous current passage successive to said path for 15 receiving said current beyond said path for extracting particles carried by said current and affording an outlet for such particles below an intermediate portion of said passage, a chamber successive to said selecting 20 means and in communication with said passage, means affording a return passage communicating between said chamber and the other side of said path, and means below said selecting means affording a wall or 25 partition between the latter and said return passage.

12. In combination, a casing, means outside of said casing for causing a fluid current therein, means for causing material to 30 descend therein in a downward path across the direction of flow of said current, selecting means at one side of said path affording a sinuous current passage successive to said path for receiving said current beyond said 35 path for extracting particles carried by said current and affording an outlet for such particles below an intermediate portion of said passage, a dust chamber successive to and receiving current from said sinuous 40 passage, and means affording a return passage above said dust chamber for returning such current above the latter to the other side of said path,

13. In combination, a casing, means for 45 causing material to descend therein in an annular path, means for causing a fluid current to traverse such descending material, an annular dust chamber surrounding said path, an annular return chamber inwardly 50 of and surrounded by said dust chamber and communicating therewith, a tangential conduit leading from said return chamber, a blower connected at its suction side to said conduit, and a return pipe communicating 55 between the blast side of said blower and the interior of said casing inwardly of such descending material.

14. In combination, a casing, means for

feeding material thereto, means for causing such material to descend therein in an annular path, a blower outside of said casing 60 for causing a fluid current to flow outwardly across such path, selecting means within said casing surrounding said path comprising reversely inclined walls providing a lower outlet for particles and affording a sinuous current passage for receiving said current successive to said path for extracting coarse particles carried by said current, an annular passage successive to and receiving 70 such current from said sinuous passage and affording communication between the outer extremity of said sinuous passage and the inner side of said path.

15. In combination, a casing, means outside of said casing for causing a fluid current to flow therein, means for causing material to descend therein in an annular downward path, annular selecting means outwardly of and concentric of said path and 80 comprising reversely inclined walls providing a lower outlet for precipitated particles and affording a sinuous outwardly extending current passage for receiving said current successive to said path for extracting coarse 85 particles carried by said current, an annular chamber successive to and communicating with said sinuous passage for receiving current therefrom, and means below said selecting means affording communication between 90 said annular chamber and the space within said annular path.

16. In combination, a casing, means outside of said casing for causing a fluid current to flow therein, means for causing material to descend therein in an annular path, means comprising a plurality of spaced annular walls surrounding said path and providing a lower outlet for precipitated material and a sinuous current passage at the 100 outer side of said path for receiving said current successive to said path for extracting coarse particles carried by said current, an annular chamber successive to and in free communication with said sinuous passage, 105 and means affording a communicating passage between said chamber and the space within said annular path.

In witness whereof, I have hereunto signed my name in the presence of two subscribing 110 witnesses.

GEORGE HOLT FRASER.
